UNITED STATES PATENT OFFICE.

JOHN PETRIE, OF GLASGOW, SCOTLAND, ASSIGNOR TO DONALDSON MANUFACTURING COMPANY LIMITED, OF GLASGOW, SCOTLAND.

DRAFT, DUST, AND WEATHER EXCLUDER FOR HINGED DOORS AND WINDOWS.

Application filed June 1, 1926, Serial No. 113,028, and in Great Britain June 6, 1925.

This invention relates to draft, dust and weather excluders for hinged doors and windows, of the type comprising a member adapted to be turned upwards into an operative position about one of its edges, which acts as a fulcrum, by means provided on the door or window.

The object of the present invention is to provide an excluder of simplified and improved construction which, for cleaning or other purposes, will be capable of being lifted freely out of a recess, serving normally to accommodate it, in the sill of the door, and which will offer no obstruction to the feet of persons passing through the doorway.

Constructional embodiments of the invention, as applied to an outside door and also to an interior door, are illustrated, by way of example, in the annexed drawings.

Fig. 1 is a fragmentary elevation of the closed door with the weather-excluding member in its operative or raised position.

Fig. 2 is a section on the line 2-2 in Fig. 1, the door being open, while Fig. 3 is a section on the same line with the door closed.

Fig. 4 is a fragmentary plan view, to a larger scale, of the door and the sill wherein said member is removably arranged.

Fig. 5 is a fragmentary plan view corresponding to Fig. 4, but showing the door closed.

Fig. 6 is a fragmentary sectional elevation showing the application of my invention to an interior door.

Fig. 7 is a fragmentary sectional elevation of a door and sill, and shows a modified form of weather-excluding arrangement.

Fig. 8 is a fragmentary sectional elevation of a further modification.

Referring firstly to Figs. 1 to 5:—

A sill *a* is arranged outside and partly beneath the door *b* and is parallel to the door when the latter is in its closed position. An upstanding part *c* is formed at the upper part of the sill and the latter is also formed with a sloping recess *d* wherein a weather-excluding member formed by a flat strip or plate *e* is loosely arranged. The top longitudinal edge of said plate is slightly below the top of the part *c* of the sill (see Fig. 2) and the ends of the plate *e* movably engage in recesses *g* formed in the two stiles *g* of the door frame, the ob-

ject of the recesses *g* being to limit the upward movement of the plate when the door is being closed. Holes *i* are formed in the sill in order to drain off water lodging in the gutter-like lower part of the recess *d*, said holes leading to the front face of the sill. A block or pintle *g* is secured to the bottom of the door with one side in the plane of the door and the other side in the plane of the hinged side of the door, said pintle projecting below the bottom of the door and being adapted to pass through a curved recess *h* formed in the part *c* of the sill *a* as the door is being closed, see Fig. 4.

When the door is open the plate *e* rests in the recess *d* in the manner shown in Fig. 2 with its top edge out of the way of the feet of persons passing through the doorway, but as the door is about to close the projecting part of the pintle *g* catches the top edge of the plate and pivots the plate about its lower edge until, when the door is fully closed, said plate is raised substantially vertical, see Fig. 3, and is prevented from further movement away from the door by the front edges of the recesses *g*. In this position of the plate its top edge rests against the door along the whole length of the bottom thereof and wind, dust, rain and sleet are effectually prevented from passing through the aperture between the bottom of the door and the sill, owing to the plate covering said aperture.

As applied to an interior door the plate *e*, see Fig. 6, is arranged in a recess *l* formed in the floor *a* and is supported on ledges *k* on opposite sides of the recess with its face flush with the floor. A plate *m* is secured to the side of the door adjacent to the plate *e* and is provided near the hinged side of the door with a hook-shaped projection *n* which runs in a curved recess *o* also formed in the floor. As the door is about to close, the projection *n* engages beneath the plate *e* and raises it, the said plate being raised still more by contact with the plate *m* on the door.

The weather-excluding plate can be readily lifted out of the recess *h*, or *l*, in order to clear the sill *a* or the recess *l*, the plate being then replaced.

In the modified construction illustrated in Fig. 7, the weather-excluding member *e* consists of a long, flat metallic plate, or strip,

which is folded over upon itself. Near its free end, the upper, folded-over portion e^1 of said plate is first bent outward away from the bottom portion e^2 of the member and then 5 forward and parallel to, but spaced from, said last mentioned portion. A long metallic strip, or plate, p is secured in a recess v in the sill a , partly at the outside and partly below the door b , said plate being formed at 10 its front and rear longitudinal edges, respectively, with upwardly projecting flanges r and s . The plate e is loosely arranged in the plate p on the sill, as shown, the outwardly and forwardly projecting part of 15 the upper portion e^1 of the plate p being arranged adjacent the flange s . Figure 8 shows a plate g^5 which can be used instead of pintle g . Member e is removed.

When the door is being closed, a pintle 20 g thereon passes through a slot h in the part e of the sill and contacts with the plate e , turning the latter upward about the bottom longitudinal edge of the portion e^2 , said edge bearing against the flange s of the 25 member p . When the door is fully closed, as shown in the figure, the plate e is inclined thereto and rests thereagainst, and thus covers the aperture t between the bottom of the door and the top of the sill. Moreover, 30 when said plate is being turned upward, the outwardly projecting part on the upper portion e^1 thereof moves around the flange s of the member p , its inner face contacting with the top of said flange when the plate 35 is in its fully inclined, or operative, position. Thus, in order to penetrate to the back of the plate e drafts, dust and rain have first to pass the additional weather-excluding means formed by the contacting 40 flange s and outwardly and forwardly projecting part on the upper portion e^1 of the plate e . A plate u secured to the outside of the door prevents any water, trickling down 45 the door, getting at the back of the plate e .

The sill a or the recessed part d thereof 50 can be of metal instead of wood and if desired the sill might be made hollow instead of solid, while flanges, or end-pieces, forming stops for limiting the upward movement 55 of the plate e , could be provided on the ends of the sill, the recesses g^1 then being eliminated. The pintle g is shown of square section in Figs. 1 to 5 and 7 but it could be of round or elliptical section or bell-shaped or be replaced by a roller or wheel.

It will be seen that in no construction described above does the weather-excluding plate e project above the top of the sill or floor, wherein it is arranged, when the door

is open and thus offers no obstruction to the 60 feet of persons passing through the doorway.

Having now fully described my invention what I claim and desire to secure by Letters Patent is:—

1. A weather-excluding arrangement for hinged doors comprising, in combination, a door sill, at least one upwardly projecting flange in the sill, a freely removable doubled metallic strip loosely arranged on the sill, 70 one edge of said strip contacting with the upstanding flange to serve as a fulcrum while the other edge projects outwardly and forwardly adjacent the said upstanding flange and means on the door for turning the strip about its loosely hinged edge into its operative position in which it is inclined to, and rests against, the door when the latter is closed.

2. A weather-excluding arrangement for 80 hinged doors comprising, in combination, a door sill, a recess in the sill formed by upstanding projections extending along the sill, a doubled metallic strip forming a weather-excluding member loosely arranged 85 in, and freely removable from, the recess and one edge of said strip bearing as a fulcrum against one of said projections, and the other edge extending outwardly and forwardly adjacent the end of this projection and a member on the door for engaging the weather-excluding member and turning it upward into its operative position against the door as the latter is being 90 closed.

3. A weather-excluding arrangement for 95 hinged doors comprising, in combination, a door sill, an inclined recess therein, an up-rising projection along the base of said recess, a freely removable doubled metallic 100 strip loosely hinged throughout its length in said recess with its lower edge bearing against said projection and its other edge projecting outwardly and forwardly adjacent the end of this projection and its top edge 105 not higher than the top of the sill, holes in said sill for draining off water lodging in said recess, a pintle on the door, a curved slot in said sill wherethrough the pintle moves, as the door is being closed, to engage 110 the strip and turn it upward about its bottom edge into its operative position, in which it is inclined to, and rests against, the door, and recesses in the stiles of the door frames for limiting the upward movement of 115 said strip.

In testimony whereof I affix my signature.
JOHN PETRIE.
